UNITED STATES PATENT OFFICE.

GEORGE C. TAFT, OF WORCESTER, MASSACHUSETTS.

IMPROVEMENT IN MILK-PAIL RESTS.

Specification forming part of Letters Patent No. 124,919, dated March 26, 1872.

SPECIFICATION.

To all whom it may concern:

Be it known that I, GEO. C. TAFT, of the city and county of Worcester and State of Massachusetts, have invented a new and useful Improvement in Milk-Pail Rests; and I do hereby declare that the following is a full, clear, and exact description thereof, which will enable others skilled in the art to make and use the same, reference being had to the accompanying drawing forming a part of this specification, in which—

Figure 1 represents a perspective view with the adjustable resting-plates turned up at right angles with the pail, ready for use, as shown at A A. Fig. 2 represents an edge or side view, detached, with resting-plate A turned down against ear-plate B, out of the way, when not in use. Fig. 3 represents a perspective face view with resting-plate A turned down. Fig. 4 represents a perspective view with the resting-plate turned up at right angles with the ear-plate B.

Similar letters of reference indicate corresponding parts.

This invention relates to an improvement in milking-pail rests; and consists in the attachment of the resting-plate to the ear-plate by a hinged joint, which is made in the usual way, leaving the resting-plate A to work in a quarter circle, as shown in Fig. 2 by dotted lines,

which resting-plate will work on its hinged joint freely, opening and closing as desired, as will be more fully described.

A is the main resting-plate. B is the ear-plate, which is secured to the pail by screws, as shown in Fig. 1. C D is the hinged joint, the parts of which are held together by a rivet, as shown in the drawing at C, Fig. 2.

The advantage which this invention has over others of its class consists in attaching the resting-plate to the ear-piece by a hinge, thereby rendering it movable, giving the user the advantage of turning the resting-plate up when in use, and down out of the way when not in use, thus doing away with all the objections which are brought against the stationary resting-plates now used.

Having thus described my invention, what I claim as new, and desire to secure by Letters Patent, is—

The combination of the plate A and ear-piece B, connected together by the hinge-joint D, forming an improved milk-pail rest, substantially as specified.

In testimony whereof I have signed my name to this specification in the presence of two subscribing witnesses.

GEO. C. TAFT.
